WINDOW SCREEN

Lawrence Thomas Ward, Kane, Pa., assignor to
 Kane Manufacturing Company, Kane, Pa., a
 corporation of Pennsylvania

Application February 29, 1932, Serial No. 595,881

11 Claims. (Cl. 156—14)

My invention relates to window screens and more particularly to a means mounted entirely upon a screen frame and which may be detachably connected to an associated window sash whereby to serve as an operator for the sash.

5 The main object of my invention is to provide on a screen a sash operator which is permanently and entirely supported upon the frame of the screen thereby forming a unit therewith. 10 Another object is to provide a sash operator having means for quickly connecting the operator to a window sash or disconnecting it from the sash.

15 Another object is to provide a unitary screen and operator in combination with means for disconnecting the operator from the sash whereby the sash and screen may be moved to their full open position.

20 Another object is to provide a unitary screen and operator that is economical and simple to manufacture, install, and maintain and wherein the unitary screen and operator as well as the associated casement offers a neat appearance particularly when the screen is removed from the 25 casement frame.

It has been the common practice in the prior art devices to provide a sash operator which is supported in one of various ways upon the sill of the window casement and which is permanently attached to the related sash by a pivotal or a slidable connection. An operator so supported, however, offers many disadvantages. They are not only expensive to construct and install but also require, in some forms, an expensive and detrimental alteration in the lower frame member of any screen applied to the frame and sash unit.

Ordinarily, such alteration of the screen frame presents the problem of devising means for rendering the screen insect proof adjacent the opening therein through which the operator passes. In the event that the screen is removed from the sash frame, the entire operator will remain supported on the casement frame thereby presenting an 45 unsightly appearance, for example during the winter period, when the screen may be removed and stored away. An operator secured to a casement frame is also objectional in that such arrangement renders it difficult to effectively and 50 quickly clean the casement sill adjacent the position of the operator.

According to my invention, the sash operator is incorporated as an integral portion of the screen itself whereby the disadvantages above mentioned are not encountered. I propose to con-

struct the screen and sash operator as one complete and compact unit whereby this unit may be easily applied to a sash frame and the operator thereafter may be quickly attached to the sash by means of a readily detachable connection. The 60 mounting of an operator on the screen is particularly adapted to side or top hinged screens as will be understood from the detailed description which follows.

In the accompanying drawings wherein a preferred embodiment of the invention is shown,

Fig. 1 is a view in cross section showing a sash in a partly open position.

Fig. 2 is a front elevation showing the sash partly open and the screen as closed.

Fig. 3 shows the screen as partly open and the sash in its closed position.

Fig. 4 shows an intermediate position of screen and sash with the operator engaging the sash.

Fig. 5 shows the operator detached from the 75 sash and the screen and sash in full open position.

Fig. 6 shows details of the operator prior to its assembly upon the screen frame.

Fig. 7 is a view showing the parts in closed 80 position.

Fig. 8 is a view in elevation of the operator with the parts in closed position.

Fig. 9 is a view in section through the plane 9—9 of Fig. 7, and

Fig. 10 is a view in cross-section on line 10—10 of Fig. 6.

Referring to the drawings in detail, in Figs. 1 and 7 is shown a side hinged screen 1 supported upon the inner face of the casement frame 2 by 90 means of upper and lower pintles 3 which rotatably engage within openings formed in the brackets 4 that are attached in any desired manner to the inner face of the frame 2. The window sash 5 is pivotally secured to the outer face of 95 the frame in the usual manner by means of the hinges 6 in a manner to swing outwardly.

A sash operator 7 provided with a handle 8 is slidably and rotatably mounted upon a casing 9 which in turn is secured, preferably by welding, 100 to the lower rail 10 of the screen frame. A pivot turret 11 is rotatably mounted within openings 12 and 13 formed in the top and bottom respectively of the casing 9. The operator 7 slidably engages a slot 14 formed transversely in the 105 turret 11, while an opening 15 formed in one corner of the casing permits angular movement of the operator to its extreme positions.

The turret is drilled and tapped at 16 to receive a headed locking bolt 17 which may be rotated 110

whereby the bolt will engage and lock the operator 7 in any desired position after its adjustment. A sash connector head 18 is pivotally mounted as at 19 upon the outer reduced end of 5 the operator which engages within a slot 20 formed in the head. A bracket 21 is attached to the lower rail of the sash 5 and a downturned hook 22 is formed as a struck-out portion of the bracket 21. The hook is adapted to engage with- 10 in a slot 23 formed in the head 18, which head is preferably tubular in cross-section and having the slot 23 formed in the lower bottom wall of the head.

The rail 10 is slotted at 25 to receive the casing 15 9 and permit the operator to swing angularly through the slot. The flanges 26 provided on the rear end of the casing 9 may be welded to the rail 10 whereby the casing and screen rail 10 become an integral unit. It will be noted in Figs. 20 20 and 8 that an appreciable length of the operator 7 is housed within the casing 9. It will be noted also that the screen is provided with a skirt like flange extension 27 which projects rearwardly from the screen frame. The main screen frame 25 and the extension 27 affords an appreciable depth to the screen frame whereby the connecting link 18 may be completely housed within the plane of the screen frame when the screen is closed against the frame 2.

30 In operation, with the screen and sash in their closed position, when it is desired to open the sash, the latter is first unlocked from the frame 2. The locking bolt 17 is rotated to release the operator 7 and the latter is then rotated clockwise 35 and pushed outwardly until the sash has reached an intermediate or an extreme position under control by the operator. With the screen and sash connected by the operator, the screen may be unlocked from the frame 2 and the screen, 40 sash, and operator may be swung fore and aft as a unit about the respective hinges. If it is desired to open the screen or sash, or either of them, to their maximum opening, the screen and sash are swung inwardly until one's arm can 45 be extended in rear of the screen in order to grasp the connecting head 18 which may then be lowered slightly whereby to release the hook 22 from the slot 23. The screen and attached operator may then be swung inwardly as far as 50 desired and the sash may be swung outwardly as far as desired. This feature of operation permits a full opening through the casement frame and affords a decided advantage in that a clear passage to the exterior of the building is obtained 55 in a manner to permit cleaning the windows or for operation of awnings.

Another advantage secured by supporting the operator upon the screen frame is that it allows the screen to be either side hinged or top hinged. 60 In all existing types of sash operators of which I am aware, it is necessary to lift the screen and remove it entirely from the opening in order to have access to the exterior. It will be noted also that the screen, sash, and operator may be 65 swung inwardly as a unit to the position shown in Fig. 3 in order to disconnect the operator from the sash and thereafter both screen and sash may be moved to their full open position as shown in Fig. 5. In this figure, a hinge is shown which permits an appreciable gap between the sash and frame in the open position of the sash whereby, 70 with the screen in its full open position as shown and the operator disconnected from the sash, an unobstructed access may be had to both sides of the sash for cleaning the same.

The provision of an operator which is readily detachable from the related sash is particularly useful when the operator is associated with and integrally mounted upon the screen, and more so, when the screen is side pivoted to the window frame.

It will be noted in Figs. 7 and 8 that a substantial length of the operator bar 7 and the connecting head 18 is mounted in the space between the front wall of the casing 9 and the face of the frame 2, while the head 18 is positioned within the plane of the screen frame. In effect, the inner end of the operator bar 7 and the head 18 constitute a toggle arrangement affording an efficient leverage and this toggle is mounted within the casing 9 and the adjacent space between the side bars of the screen frame in a manner to permit the screen to be positioned closely adjacent the sash.

While I have shown a preferred form and arrangement of my invention for the purpose of illustration, it is to be understood that various modifications thereof are contemplated as will be embraced within the scope of the claims which follow.

I claim:

1. A screen comprising a frame member, means for pivotally connecting said member to a casement frame, a sash operator, a casing supported on said member, and means for slidably and rotatably securing said operator within said casing to provide a unitary screen and operator unit.

2. A screen comprising a frame member, means on said member for pivotally connecting said member to a casement frame, said member having an opening therethrough, a sash operator extending through said opening, a bracket secured to said frame member adjacent said opening, means on said bracket displaced from said member and providing a fulcrum for pivotally supporting said operator in a position parallel to the member.

3. A screen comprising a frame member, a sash operator pivotally supported entirely upon said member, means for pivotally connecting said frame member to a casement frame, said member having a slot therethrough, said operator being movable through said slot and means for connecting said operator to a sash whereby the screen, sash and operator may swing as a unit, or said sash may be operated independently by said operator said frame member and operator being removable from the casement frame as a unit.

4. A screen comprising a frame, a casing integrally attached to said frame, a sash operator rotatably secured to said casing with one end of the operator extending within the casing, means for connecting said end to a sash said operator being movable to a position close to said frame and parallel thereto.

5. A screen comprising a frame member, a sash frame, said frame member and sash frame being pivotally connected together, a sash operator adjustably mounted on said frame member, said member being provided with an opening, a sash connecting link pivotally connected to said operator and being operably movable through the opening, a flange extension on said frame member adapted to contact the sash frame when the screen is closed, said link being housed within the plane containing the frame member and flange extension when the screen member is closed against the sash frame.

6. A screen comprising a frame member, means

for connecting said member to a casement frame, a sash operator, and fulcrum means on said member for supporting said operator upon the member, said fulcrum means permitting the operator to move to a position parallel to the member and means for pivotally connecting one end of said operator to a fixed point on a sash.

7. A screen including a frame member, said frame member having hinge means for side attachment to a casement frame, a sash operator, said member being provided with an opening, a casing permanently attached within said opening, and fulcrum means on said casing providing a slideable and pivotal support for the operator.

8. A screen comprising a frame member, means for connecting said member to a sash frame, said member having an opening therethrough, a casing secured to said member adjacent said opening, a sash operator fulcrumed in said casing, means for connecting the inner end of said

operator to a fixed point on a sash, said operator being movable to a position parallel to the frame member with the inner end of the operator housed within the casing.

9. A screen as set forth in claim 8, wherein the fulcrum point of the operator is positioned adjacent one side of the casing.

10. A screen as set forth in claim 8, wherein the operator is slidably and rotatably mounted within the casing.

11. A screen comprising a frame member, said member having an opening therethrough, a bracket secured to said member opposite to said opening, a sash operator slidably and rotatably mounted on said bracket, a link connected to the inner end of the operator and having means at its free end for attachment to a sash, the fulcrum point of said operator being displaced from said frame member whereby the operator may be positioned parallel to said frame member.
